UNITED STATES PATENT OFFICE.

JOHN RAMSLIE, OF BURLINGAME, CALIFORNIA.

METHOD AND MEANS FOR PITTING FRUIT.

Application filed October 9, 1926. Serial No. 140,559.

My invention relates to the method and means for removing pits from the pulp of cooked fruit, and is applicable to various fruits such as for example prunes, apricots, 5 peaches, dates and the like.

The general object of my invention is to produce a separation of the fruit pulp from the pits by a fluid blast under pressure and so employed as to cause the pulp and pits to 10 be separately directed to suitable receptacles, the use of compressed air or steam being employed for the purpose.

The nature of my invention and its distinguishing features and advantages will 15 clearly appear as the description proceeds.

Reference is to be had to the accompanying drawings forming part of this specification, it being understood that the drawings are merely illustrative of one example of the 20 invention.

Figure 1 is a vertical section of an apparatus for carrying out my invention, the plane of the section being indicated by the line 1-1 in Figure 2.

25 Figure 2 is a sectional plane view, the section being taken on the line 2-2 in Figure 1.

Figure 3 is a detail in transverse vertical section on the line 3-3 in Figure 2.

30 Figure 4 is a vertical section of the lower end of the pipe for directing the blast of air or steam against the fruit on the screen.

Figure 5 is a detail in vertical section of the central post and its supporting means.

35 In carrying out my invention in accordance with the illustrated example a screen 10 is provided which, in the preferred and advantageous form of the invention is made in the form of a ring of unbroken con-

40 tinuity; the screen 10 is here shown as having support at the top of a central post 11. Cross arms 14 are provided as part of the screen frame and pivoted by pin 20 to said post 11. The frame is completed in the

45 form shown by space rings 15 adjacent the inner and outer edges of the screen; said rings being secured by bolts 16. In line with post 11 is aligning post 17 receiving a screw 18 at the lower end; said screw having

50 head 19 forming a socket resting on the bearing pin 20 on the post 11. Post 11 has a depending pin 12 at the lower end which is

stepped in a bearing 13 on floor "A" while the upper post 17 is secured in a suitable manner as by angle brackets 21 to the ceiling "B" or other overhead support. Braces 22 extend obliquely from post 17 to ceiling "B".

Above the screen 14 is an arcuate hopper 23 having top frame 25 suspended by hanger rods 26 from ceiling "B".

The numeral 27 indicates a pipe extending downward from a pressure box 28 having an inlet pipe 29 for compressed air or steam whereby to direct the fluid from pipe 27 against the screen 10.

The numeral 30 indicates a kettle suspended above the screen and adapted to contain a quantity of fruit to be pitted, said kettle being shown as hung by a hanger rod 31 from the ceiling "B." Pipe 27 at its discharge end has a laterally deflected nozzle 32. Formed integrally with one wall of said nozzle is a short vertical partition 33 dividing the outlet or lower end of pipe 27 into two discharge passages.

With the described construction the fruit is dumped or raked from the kettle 30 and will be directed to screen 10 through the open bottom of hopper 23. The blast of air or steam escaping from the pipe 27 at one

30 side of partition 33 which will direct the blast against the fruit (b) passing beneath the discharge end of said pipe 27. The described mounting of the screen 10 permits

35 of the same being manually turned, but it will be readily understood that the said screen may be turned by any suitable means. The blast of air strips the pulp from the pits indicated at "b" and as said pits "b" travel

40 beneath the laterally deflected nozzle 32 a second blast of air or steam will be directed at the other side of the partition 33 onto said pits. The first mentioned blast of air or steam will cause the stripped pulp to be directed to any suitable receptacle 34 while stripped pits "b" will travel toward any

45 suitable receptacle indicated at 35.

I would state furthermore, that the described means for carrying out my invention 50 constitute one practical construction for the purpose, but it will be understood that I do not limit myself to the exact details illustrated since, manifestly, the same can be con-

siderably varied without departing from the spirit of the invention as defined in the appended claims.

I claim:

- 5 1. In a method of removing the fruit pulp from pits of cooked fruit, the step of directing an air blast against the softened fruit with a force to strip the pulp from the pits.
- 10 2. In a method of separating the pulp of cooked fruit from pits, the step of causing an air blast to strip the softened pulp from the pits and direct the pulp and pits in different directions to effect separation of the same.
- 15 3. In an apparatus for removing fruit pulp from pits and separating the two, a screen, means to direct the fruit onto the screen, and a blast pipe for directing the

fluid under pressure against the fruit on the screen, said blast pipe having a duplex outlet, one of the outlets having a laterally deflected nozzle.

4. In an apparatus for removing fruit pulp from pits, a central post, a screen frame 25 turnably mounted on said post, a screen on said screen frame, a post above the screen, a turnable support on the first mentioned post, a hopper disposed above said screen and having an open bottom to direct the 30 fruit onto the screen, a blast pipe adapted to direct a blast of fluid under pressure against the fruit on the screen, and a fruit holder suspended above the hopper in advance of said blast pipe and adapted to hold the 35 fruit to be deposited onto the screen through said hopper.

JOHN RAMSLIE.
